UNITED STATES PATENT OFFICE

111,798

DESIGN FOR A COMBINED PHONOGRAPH AND PICTURE PROJECTOR

Svatopluk C. Volney, New York, N. Y., assignor to American Proca Corporation, a corporation of
New York

Application June 13, 1938, Serial No. 77,803

Term of patent 7 years

To all whom it may concern:

Be it known that I, Svatopluk C. Volney, a citizen of Czechoslovakia and resident of the city, county and State of New York, have invented a new, original, and ornamental Design for a Combined Phonograph and Picture Projector, of which the following is a specification, reference being had to the accompanying drawing, forming part thereof.

I claim:

The ornamental design for a combined phonograph and picture projector, substantially as shown.

SVATOPLUK C. VOLNEY.
